The ornamental design for a positioning bed pad as shown and described.

DESCRIPTION

FIG. 1 is a front perspective view of a positioning bed pad, showing my new design;

FIG. 2 is a rear perspective view thereof;

FIG. 3 is a front elevational view thereof;

FIG. 4 is a rear elevational view thereof;

FIG. 5 is a left side view thereof, the right side view being a mirror image of FIG. 5;

FIG. 6 is a top plan view thereof, the bottom plan view being a mirror image of FIG. 6;

FIG. 7 is a partial enlarged view of FIG. 5;

FIG. 8 is a partial enlarged view of FIG. 5;

FIG. 9 is a partial enlarged view of FIG. 6;

FIG. 10 is a partial enlarged view of FIG. 6;

FIG. 11 is a front perspective view of the positioning bed pad in a detached state; and,

FIG. 12 is a rear perspective view of the positioning bed pad in a detached state.

The evenly dashed broken lines represent suture lines forming part of the claimed design. The dot-dash broken lines depict the bounds of the enlarged views that form no part of the claimed design.
